FOLDING CHAIR

Werner E. Clarin, Muncie, Ind., assignor to
Durham Manufacturing Company, Muncie,
Ind., a corporation of Indiana

Application October 23, 1937, Serial No. 170,514

4 Claims. (Cl. 155—142)

The present application relates to a folding chair, and more particularly to folding chairs of the type in which the seat member is pivoted upon a horizontal axis intermediate the front and rear edges of the seat member. The primary object of the invention is to provide automatically operating means for locking the seat member in seating position, to prevent accidental collapse of the chair.

5 Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, so long as the scope of the appended claims is not violated.

20 Fig. 1 is a side elevation of a chair constructed in accordance with the present invention.

Fig. 2 is an enlarged fragmental elevation of the essential details of the present invention, the parts being shown in a partially collapsed condition; and

25 Fig. 3 is a fragmental horizontal section taken substantially on the plane indicated by the line 3—3 of Fig. 1, and looking in the direction of the arrows.

30 Folding chairs of the type in which the seat member is pivoted upon a horizontal axis intermediate the front and rear edges thereof are subject to the decided disadvantage that, if weight is applied to the seat member at a point 35 behind the axis of said seat member, there is grave danger of collapse of the chair, resulting from turning of the seat member about its axis, thereby pulling the legs together; and often resulting in serious injury to the user. In spite 40 of the fact that chairs are intended only to provide seats, while stepladders are intended for use where a person desires to reach an elevated object, people insist upon standing on chairs, on many occasions, in order to save themselves the trouble of going for a stepladder. On numerous 45 occasions, people have stepped onto folding chairs of the general type of that here under consideration, have thoughtlessly applied their weight primarily, if not solely, to the portion of 50 the seat behind the pivotal axis of the seat, and have thereby caused the collapse of the chair, whereby they have been thrown to the floor, at least one leg being caught within the chair structure; and bone fractures and other serious 55 injuries have resulted.

It is the object of the present invention to provide a chair of the type here under consideration in which there is incorporated means for automatically preventing such accidents.

In the accompanying drawing, I have shown 5 only one side of an embodiment of my invention; but it is to be understood that the two sides of the chair are entirely symmetrical; so that only the illustrated side will be described. In said illustrations, I have shown a front leg 10 which 10 may be formed of rod or tube stock bent to the shape of an inverted U, the loop at the top supporting a back rest element 11. Intermediate the ends of the legs 10 there are secured brackets 12 to which are hinged or pivoted legs 13, 15 through the medium of pivot pins 14.

The seat member 15 is pivotally mounted, upon a rod 16, between the legs 10; the rod 16 being positioned intermediate the front and rear edges 20 of the seat member 15, and passing through angle irons 17 secured to the opposite side edges of the seat member.

A link 18 is pivoted, as at 19, to one of the legs 13; and it will be understood that, whereas I consider it to be highly desirable to provide links 25 18 on both sides of the chair, a construction in which only one link 18 is used is within the spirit of my invention.

The opposite end of the link 18 is provided 30 with a slot 20 elongated in the direction of the long dimension of said link; and said slot receives a pin 21 projecting laterally from the member 17.

A second slot 22 opens through the lower edge 35 23 of the link 18, and is formed with an extension 24 projecting longitudinally of the link 18 away from the pivot 19. A second pin 25, spaced rearwardly from the pin 21, projects laterally from the member 17.

It will be seen that the legs 10 and 13 are 40 so related that they may assume a position of substantial parallelism, or any one of a plurality of positions of relative angularity. As the legs 13 are swung outwardly away from the legs 10 and out of a position of parallelism, the link 18 45 will operate to swing the seat member 15 from a position of substantial parallelism with the legs 10 toward the seating position illustrated in Fig. 1. As the elements approach the position of Fig. 1, the pin 25 will enter the slot 22, and will 50 strike the upper wall of said slot to arrest further movement of the seat member 15 about its axis 16. In this position of angularity of the legs 10 and 13, the chair corresponds closely to former folding chair constructions of the type here un- 55

der consideration. Because of the provision of the elongated slot 20, however, it will be seen that it is possible to move the legs 13 to a position of greater angularity with respect to the legs 10. During such movement to the maximum degree of angularity, the link 18 is moved rearwardly with respect to the seat member 15, whereby the pin 21 is caused to assume the relative position of Fig. 1, and the pin 25 is caused to enter the extension 24 of the slot 22. Thus, the parts assume the positions illustrated in Fig. 1.

When the parts are positioned as illustrated in Fig. 1, the engagement of the pin 25 with the upper wall of the slot extension 24 prevents further clockwise movement of the seat member 15 about its axis 16; while the engagement of the pin 25 with the shoulder 26 prevents counterclockwise movement of the seat member 15 about its axis 16. No degree of force, less than that degree required to cause breakage, applied to the seat member 15 in any direction can cause movement of the said seat member about its axis 16. The lock provided by the described organization cannot be released except by preliminary movement of the legs 13 toward the legs 10. Any force applied to the chair in a downward direction tends to spread the legs 13 away from the legs 10, rather than to cause the legs 13 to approach the legs 10.

The chair cannot be moved again to folded position except by applying force in a substantially horizontal direction to move the legs 13 toward the legs 10 to shift the extension 24 away from pin 25.

I claim as my invention:

1. A folding chair comprising two pairs of legs hinged together adjacent their upper ends, a seat member pivotally mounted between one pair of legs on an axis intermediate the front and rear edges of said seat member, a link pivoted to one of the other pair of legs and having a lost-motion pivotal connection with said seat member, and cooperating means on said link and on said seat member operable, in one position of said link with respect to said seat member, to hold said seat member against movement about its pivotal axis.

2. A folding chair, comprising a pair of front

legs, a pair of rear legs pivoted, at their upper ends, to said front legs, a seat member pivotally mounted between said front legs on an axis intermediate the front and rear edges of said seat member, a link pivoted at one end upon one of said rear legs and having a pin-and-slot connection with said seat, said link being formed with a further slot, and a pin on said seat member engageable, at times, in said last-mentioned slot to hold said seat member against movement about its pivotal axis.

3. A folding chair, comprising a pair of front legs, a pair of rear legs pivoted, at their upper ends, to said front legs, a seat member pivotally mounted between said front legs on an axis intermediate the front and rear edges of said seat member, a link pivoted at one end upon one of said rear legs and having a pin-and-slot connection with said seat at a point between the pivotal axis of said seat and the rear edge thereof, said link being formed with a further slot, said last-mentioned slot opening through the lower edge of said link and being provided with an angularly related extension projecting away from said first-mentioned end of said link, and a pin on said seat member enterable in said last-mentioned slot, and shiftable, upon continued extending movement of said rear legs, into the extension thereof.

4. A folding chair, comprising a pair of front legs, a pair of rear legs pivoted, at their upper ends, to said front legs, a seat member pivotally mounted between said front legs on an axis intermediate the front and rear edges of said seat member, a link pivoted at one end upon one of said rear legs and having a pin-and-slot connection with said seat at a point between the pivotal axis of said seat and the rear edge thereof, said link being formed with a further slot, said last-mentioned slot opening through the lower edge of said link and being provided with an angularly related extension projecting away from said first-mentioned end of said link, and a pin on said seat member automatically movable, as said rear legs and front legs are swung to open the chair, into said slot and subsequently into the extension thereof.

WERNER E. CLARIN.
